CLAIM

The ornamental design for a mountaineering tool for rope climbing, as shown and described.

DESCRIPTION

FIG. 1 is a perspective view of a mountaineering tool for rope climbing, showing our new design;
FIG. 2 is a side view thereof;

FIG. 3 is a side view thereof, from a side different than FIG. 2;

FIG. 4 is a side view thereof, from a different angle than FIG. 2;

FIG. 5 is another side view thereof; and,

FIG. 6 is a top view thereof.
